UNITED STATES PATENT OFFICE

139,759

DESIGN FOR A LIFT TRUCK

George V. Johnson, Portland, Oreg., assignor to
Willamette Hyster Company, Portland, Oreg.,
a corporation of Oregon

Application July 17, 1944, Serial No. 114,429

Term of patent 14 years

(Cl. D14—3)

To all whom it may concern:

Be it known that I, George V. Johnson, a citizen of the United States, residing at Portland, in the county of Multnomah and State of Oregon, have invented a new, original, and ornamental Design for a Lift Truck, of which the following is a specification, reference being had to the accompanying drawings, forming part thereof.

Fig. 1 is a view in perspective, taken from the front left of the lift truck showing my new design; and

Fig. 2 is a view in perspective, taken from the rear left of the lift truck.

The appearance of the opposite or right side of the design is substantially the same as that shown in the left hand views.

I claim:

The ornamental design for a lift truck, as shown and described.

GEORGE V. JOHNSON.
